UNITED STATES PATENT OFFICE.

ADDISON T. SAUNDERS, OF AKRON, OHIO, ASSIGNOR TO A. G. SPALDING & BROS., OF NEW YORK, N. Y., A CORPORATION OF NEW JERSEY.

GAME BALL.

Application filed February 3, 1927. Serial No. 165,663.

My invention relates to improvements in that class of balls known as game balls, or playing balls. More directly it relates to balls of lighter weight than heretofore used 5 in such games, and having other distinctive characteristics which render it suitable, for practice by badminton players, instead of the shuttlecock used in that game, and for a modified, or light, tennis.

10 Played under the rules of badminton and with the light badminton racket, this ball has the advantages that it is not injured by the down stroke, a single one of which frequently wrecks a shuttlecock by breaking the shafts 15 of the feathers and thus making it unplayable, and further that the great overhead space demanded for the flight of the usual feathered shuttlecock is not required.

This is due to the fact that when the ball 20 is struck it travels in the direction of the impulse from the racket, as does the usual tennis ball, while a characteristic of the shuttlecock is that when struck with a directly forward, horizontal impulse while pitching in 25 an almost vertical direction, which is a part of its most frequent trajectory in play, it takes a sharp upward angle of approximately forty-five degrees from the horizontal as it leaves the racket.

30 The importance of a substitute for the shuttlecock will be seen when it is considered that the minimum height of ceiling for badminton courts is named as twenty-five feet, owing to this lofting action.

35 When a court with this great overhead space is not available an interesting game may be played with one of the forms of my invention, described below, and under the rules of badminton.

40 When the ball is played under the rules of tennis, a light racket such as the badminton racket is preferable.

It will be understood that these implements, a racket of only about one-third the 45 weight of the usual tennis racket, and a ball correspondingly light, make the game of tennis available for children and those adults who have not the strength of wrist to wield, pleasurable, the heavier racket.

50 By the expedients described below I am able to shorten the flight of the ball so that the game, under the regular tennis rules, may be played in the space of a badminton court. It will be seen that this is very desirable, mak-

ing the game available for many in the 55 smaller gymnasiums, playgrounds and lawns.

Figure 1 shows a thin walled ball according to my invention having minimum perforation of its wall.

Fig. 2 is a view of a ball having medium 60 perforation of its wall.

Fig. 3 is a view of a ball having maximum perforation of its wall.

Fig. 4 is a cross section of a freely perforated ball upon impingement on the top edge 65 of the net.

In all the forms shown in Figures 1, 2, and 3 the ball has a thin wall, for example, say $\frac{1}{32}$ of an inch.

The ball of Fig. 1 has one small perforation at 1; that of Fig. 2 has perforations at 2, and the ball of Fig. 3 has perforations at 3.

The novel characteristics of my invention are:

(1) A ball of hollow construction with 75 rubber wall of such thinness as has not heretofore been employed in any game ball, and with but slight resistance to indenting, yet resilient; having the quality of quick return to spherical form when distorted.

(2) In combination with such a wall, a 80 state of non-inflation, that is to say, that at rest the air content of the ball is one atmosphere, or at equilibrium with the surrounding air.

(3) For the maintenance of this state of 85 equilibrium and for the further purposes described below, a perforation or plurality of perforations through the wall.

(4) When I employ a plurality of perforations, the spacing of these uniformly and 90 geometrically with relation to the surface of the ball.

While I do not wish to limit myself to any 95 exact figures or dimensions, I would say that for the games mentioned above, I prefer a ball of about $2\frac{1}{4}$ inches diameter, and in the case of badminton a weight of about $\frac{1}{6}$ to $\frac{1}{4}$ oz. with a wall thickness of only about twenty thousandths inches (.020''), and, as 100 the missile is always in the air when in play, that is, is not required to rebound from the floor, I prefer to provide a plurality of perforations to such amount as to permit the free expulsion of the air content at the instant of impact of the racket. This not only 105 slows down the pace by avoiding action of the resiliency of the air, but further retards

flight-length and pace by increasing the friction or resistance of the atmosphere, the air through which the ball flies.

It will be plain that when a plurality of 5 perforations is employed their geometric placing upon the surface is desirable. Such arrangement maintains balance as to weight of the various parts of the wall, equalizes the air resistance and avoids inequality of action 10 in the various parts of the resilient wall which would result from clustering the perforations or distributing them unequally.

I find that I can secure any shade of deadening of rebound, between the ball with only 15 the minimum perforation or "breather" to one wherein the total area of perforations is so great that the ball, in spite of the resilient quality of the wall, has practically no rebound.

20 Therefore, it will be understood I can "tune" or adapt balls to any character and behavior to meet various demands.

For instance, by employing a perforation of only the limited capacity required to permit 25 the intake of air in response to the effort of the resilient wall to return to spherical form after being indented or depressed, (and thereby losing a portion of its air content,) I make available and operative the resiliency 30 of the contained air as well as of the wall, since, under the quick impact of the racket, but a very slight portion of the air escapes through the breather.

Thus, and by a slight increase in the weight 35 of the wall, I produce a ball of proper resilience and playing qualities for the game of light tennis, wherein a specified degree of rebound is important. This light ball, as indicated above, is adapted to be played with 40 light badminton rackets, under tennis rules. And, as indicated above, by the use of the expedients stated for controlling flight, more particularly in this case by keeping the wall thin, I secure a ball adapted to short courts.

45 A desirable property of the ball, not mentioned above, functions when the missile impinges on the top edge of the net. It is desirable in some games that when this occurs the missile shall be directed downward there- 50 by. This is important in skilled play in the game of badminton. The shuttlecock is so deflected.

The direction of flight of a firm or nearly rigid ball such as the usual, inflated, tennis ball, is not materially affected by such impingement.

Owing to the thin and yielding wall of the ball of my invention, it is locally and

sharply indented by such contacts, with the effect of a clinging action on the edge of the 60 net in passing, which causes it to imitate the action of the shuttlecock under like conditions.

No game ball, prior to my invention, has had a wall of such character as to permit of 65 being deeply and sharply indented within a small or limited area of its surface without materially altering the contour of and distorting the major part of the surface of the sphere. It will be seen that this is desirable 70 for the reason above given.

Since, in the case of a ball featured with the free perforation, the compression of air within is, upon impact, relieved by the perforation, the ball must recover its shape en- 75 tirely by reason of the resiliency of its wall, and does not offer any air resistance against the inner surface of the concavity or indentation, as does the ordinary non-perforate ball, which effectively resists indentation by rea- 80 son of the contained air being compressed and which is thereby distorted in other parts when impact with a surface takes place. The ordinary non-perforate ball is merely flat- 85 tened upon impact with a flat surface and is not indented.

By the construction and expedients herein above set forth, a thin walled ball for badminton, light tennis and the like is provided of a character and behavior clearly distin- 90 guished from the usual game balls which, owing to greater weight, thickness and stiffness of wall, internal air pressure or other characteristics, are incapable of being deeply indented and of exhibiting the behavior, in 95 play, of this invention.

I claim—

1. A hollow game ball as a substitute for the shuttle in badminton or for light tennis and the like, comprising a thin resilient perforated indentable rubber wall, said wall being adapted to be locally sharply indented upon impact of slight force and when so indented in any portion to retain its spherical form in other portions, and to recover from indentation, the perforations being of small size such that the sphericity of the ball will be substantially unimpaired, substantially as described.

2. A hollow playing ball of resilient rubber having a diameter of approximately 2 $\frac{1}{4}$ inches and a wall thickness of approximately .02 of an inch, said resilient wall being perforated, substantially as described.

In testimony whereof, I affix my signature.
ADDISON T. SAUNDERS.
